UNITED STATES PATENT OFFICE.

JOHN E. DANIELS AND GEORGE S. KENDALL, OF BOSTON, MASSACHUSETTS.

IMPROVED CLOTHES-WRINGER.

Specification forming part of Letters Patent No. 35,810, dated July 8, 1862.

To all whom it may concern:

Be it known that we, JOHN E. DANIELS and GEORGE S. KENDALL, of Boston, in the county of Suffolk and State of Massachusetts, have invented certain Improvements in Clothes-Wringing Machines, of which the following is a full, clear, and exact description, reference being had to the accompanying drawings, making part of this specification, in which—

Figure 1 is a vertical section through our improved machine; Fig. 2, a view of one of the standards and our improved clamp.

The object of our present invention is to produce a clothes-wringing machine which is simple and durable in its construction and in which the pressure of the springs is so applied to each bearing of the upper roll which rises and falls that when an article is pressed between the two rolls A and B which is thicker on one side or toward one end of the rolls than the other the pressure of the springs may be continued and applied to both sides of the article being pressed, notwithstanding that one end of the roll is raised higher than the other; and our invention consists in the clothes-wringing machine which we will now describe in such terms that others skilled in the art may understand and use our invention.

In the said drawings, A A' are two standards, which are clamped to the tub or other support in a manner which will be presently described. The lower roll, B, to the shaft of which is attached a crank, C, has the bearings of its shaft in these two standards. The shaft of the upper roll, D, has its bearings in two blocks or boxes, a, which are free to slide up and down in vertical grooves b in the standards. A rigid bar, E, rests in these grooves on top of the two boxes. A cross-piece, F, connects and braces the upper ends of the two standards A A'. Two pieces of wood, G and H, which are arched in the middle at c to form springs, have their ends fitting in the vertical grooves b in the standards. The lower one, H, rests at the middle of its length on the bar E with a block of rubber, I, interposed, (a rod, f, keeping the rubber in place.) A thumb-screw, K, which works

in the top bar or cross-piece, F, bears on the middle of the upper spring; G. By this screw the requisite amount of pressure may be applied to the roll D through the springs G and H.

It is evident that, as the pressure of these springs is applied to the middle of the bar E, which pivots on the rubber bearing I, the roll D may be raised higher at one end than at the other, and the pressure will still be applied throughout its whole length. The bar E and springs G and H, being made of wood, are not liable to rust and stain the clothes; but metal springs properly coated may be used.

Various kinds of clamps have been employed to secure the standards A A' to the tub or other vessel to which the wringing-machine is to be attached; but as the tub which is generally used is circular in form, and it is desirable not to mar and bruise its edge, we have adopted the following-described attachment: To one side of each standard A or A' is permanently attached a leg, M, with a space between its lower end, f, and the end g of the standard, as shown in Fig. 2, the lower end of the standard being rounded to prevent bruising the tub. A pad or shoe, O, (which is rounded on the side which comes in contact with the tub,) has two pins, h, attached to it, which slide in holes in the end of the leg M, the pad being pressed away from the leg by a thumb-screw, P. This permits the machine to be clamped to the tub without the binding-screw P bruising the edge of the tub.

We do not claim the rubber bearing or block I as a spring, as a wooden block would answer for a bearing on which the bar E could pivot.

What we claim as our invention, and desire to secure by Letters Patent as an improvement in clothes-wringing machines, is—

Applying the pressure of the springs G and H to the boxes a through the middle of the length of the bar E, substantially as described.

J. E. DANIELS.
GEORGE S. KENDALL.
